SPINDLE TIP TYPE SPINNING DEVICE
Claude Delesalle, 10 Blvd. Vauban, Lille, France
Filed Nov. 21, 1957, Ser. No. 698,009
Claims priority, application France Nov. 21, 1956

8 Claims. (Cl. 57—73)

The present invention relates to an entrainment or feed arrangement of the thread on the spinning and twisting spindles which enables a reduction in the number of breakages of the threads and to increase the speed of the spindles.

Accordingly, it is an object of the present invention to provide an arrangement which produces a torsion in that part of the drawnout roving which is located between the pair of delivery cylinders and the guide disposed above the head of the spindle.

In practice it has been found in effect that it is at this particular place that the majority of ruptures or breakages occur; for, by reason of the imperfect distribution of the torsion, this part of the thread is less sturdy and cannot always resist to the tension forces of the traveler.

In order to obviate this inconvenience, it has been suggested in the prior art to replace the guide, for instance, in the form of an auger-like gimlet, by a rotating turbine positively controlled by a mechanical system, and to pass the thread into this turbine in order to impart thereto a false torsion. However, the great speed of rotation of the turbines poses problems which are difficult to resolve insofar as the construction of bearings as well as the mechanical control thereof are concerned.

It has also been attempted to reduce the number of breakages by utilizing so-called "pointed-spindle" devices or "reduced-balloon spinning devices." In these prior art devices which enable to effectively remove the thread from the tension force of the traveler or at least lessen such force, the thread is rolled over several coils about an extension or projection above the spindle, which is provided with an attachment device. As a result of such an arrangement, the part of the thread located in the critical zone is at least partly removed from the tensional stresses of the traveler, this force or stress being thereby localized between the coils wound on the spindle and the traveler, that is, on that part of the thread having already acquired its entire resistance. However, these prior art arrangements offer serious inconveniences and disadvantages among which may be mentioned the following:

(1) Even if well-polished annular members are used, different frictional coefficients exist between the annular members and the travelers of the same machine. It would, therefore, be necessary in order to obtain uniform operating conditions to carefully select for each particular case the appropriate weight of the travelers in order to avoid that the brakage is either too strong if the winding is too much accentuated or, on the contrary, too weak if the winding is insufficient.

(2) The amplitude of the reduced balloon varies according to the degree of brakage in such a manner that the balloon is either too small or too large. It is obvious that under these conditions it is difficult, and in certain cases even impossible, to determine the exact weight of the traveler which assures an average tension.

(3) In practice, it is extremely difficult to obtain, by means of a central control, the same number of windings along the entire length of one continuous batch to be spun, given the fact that the variations in the friction in different spindles and the variations of adherence of the tubes or bobbins are amplified by the capstan effect.

The device and apparatus according to the present invention avoid all the disadvantages and inconveniences of the prior art and enable the realization of a pre-torsion in the thread without the use of a special member having

2

a positive control, and without necessitating the winding of the thread in spiral form about the spindle.

The device in accordance with the present invention is characterized by the fact that it comprises an entrainment or feed member fixed to the end of the spindle and at least one annular guide member assuring permanent contact of the thread on this entrainment or feed member which in turn then assures the pre-torsion of the thread.

Such an arrangement and device differs totally from anything known in this field to date by reason of the fact that the arrangement and device according to the present invention do not necessitate a control system nor bearings as in the case of rotating turbines nor winding of the thread about the spindle as in connection with the "pointed" spindles.

The guide member for the thread, preferably in the shape of an annular member, is disposed below the entrainment or feed member and is fixed on the thread guide. It is also understood that it is possible to provide other annular guide members below the first guide members in order to further reduce the size of the balloon or to permit the suppression of separators.

On the other hand, with a view to enable the control of the pressure of the thread against the entrainment or feed member, the position of the upper annular guide member for the thread and of the thread guide is adjustable.

The guide is provided with an auger-like gimlet or preferably with a plate, notched in the shape of a V and possibly provided with a retaining finger or nose member. The annular guide member is a ring which may be either continuous or non-continuous, disposed about the spindle and fixed directly on the thread guide or only on a rod disposed near the spindle.

The entrainment or feed member may be formed integrally with the spindle, or preferably may be removable and interchangeable. The entrainment or feed member may also have any appropriate diameter, profile and height, may be shaped as a disk or may have the shape of a cylinder or of a truncated cone. The entrainment or feed member may have a surface which is more or less adherent or rough or may be provided with indentations or projections of any number according to any suitable arrangement, however, always enabling to the thread the necessary sliding movement. The indentations may be formed by slots of slight depth which are disposed laterally and the angle of which must be so calculated that the thread may readily pass from one slot to another.

The entrainment or feed member may be made of any suitable material such as metal, rubber, plastics or mineral material, etc.

The entrainment or feed member has preferably a diameter at the most as large as that of the spindle in order to permit the emplacement and removal of tubes or bobbins which are mounted on the spindle.

Accordingly, it is an object of the present invention to provide an anti-balloon arrangement for spinning machines which is simple in construction and effective in operation.

It is still another object of the present invention to provide a guide system for the thread of a spinning and twisting device in which a predetermined torsion is imparted to the thread so as to reduce the breakages and enable relatively high-speed operation.

Still another object of the present invention is to provide a means for imparting a torsion to the thread without any separate control device which needs to be positively driven and without having to wind the thread spirally about the spindle.

These and other objects, features and advantages of the present invention will become more obvious from the following description when taken in connection with the

accompanying drawing, which shows, for purposes of illustration only, one embodiment in accordance with the present invention, and wherein:

FIGURE 1 is a partial side elevational view of an anti-balloonning arrangement in accordance with the present invention,

FIGURE 2 is a partial top plan view of the arrangement of FIGURE 1,

FIGURES 3 and 3A are respectively a plan view and a side elevation of a form of thread guide differing from that shown in FIGURES 1 and 2,

FIGURES 4 and 4A are like views of another form of thread guide,

FIGURES 5 and 5A are like views of still another form of thread guide,

FIGURES 6 and 6A are respectively a plan view and a side elevation of a form of annular guide member differing from that shown in FIGURES 1 and 2,

FIGURES 7 and 7A are like views of a still further form of annular guide member,

FIGURES 8 and 8A are respectively a plan view and a side elevation of a rod mounting for a thread guide,

FIGURES 9 and 9A are respectively a side elevation and a plan view of a form of the entrainment member differing from that shown in FIGURES 1 and 2,

FIGURES 10 and 10A are like views of a further form of the entrainment member, and

FIGURES 11 and 11A are like views of a still further form of the entrainment member.

Referring now to the drawing, wherein like reference numerals are used to designate like parts, reference numeral 1 designates the delivery cylinders or metering rolls which deliver the thread 2. The thread 2 passes first past the thread-guide member 3, to be more fully described hereinafter, and mounted on a hinged member 4. After passing through the thread-guide member 3, the thread 2 proceeds tangentially along the knurled portion 5 of the head of the spindle 12 forming an entrainment or feed point, thereafter passes along the inside of an annular guide member 6 rigid with the member 4, thereupon, after having formed a relatively small balloon 7, passes within the annular member 8 and finally into the traveler 9 which turns about the annular member 10 fixed on the annular support member 11. The thread 2 is wound on the bobbin 13 mounted on the spindle 12 in any suitable manner and according to any known pattern and winding method.

The annular guide member 6 is rigidly connected with the thread-guide member 3 or is formed integral therewith.

The annular member 8 is constantly maintained essentially in the center of that portion of the thread 2 which is located between the annular guide member 6 and the annular member 10 by means of a support member 14 which itself is actuated in any suitable manner to provide a reciprocating motion as indicated by the arrows.

FIGURE 2, which is a plan view of FIGURE 1, shows the thread 2, the thread guide member 3 mounted on the hinge member 4 thereof and formed by a plate provided with a notch in the shape of a V, the knurled head portion 5, the annular member 6 and the ballooning control annular member 8.

The height of the guide 3 above the spindle 12 varies according to the diameter and head of the spindle. As an illustration, for a spindle head portion 5 of 16 mm. in diameter, the height of the guide 3 must be about 15 mm. with respect to the spindle head portion 5.

Since the drive means to provide the reciprocating movement indicated by the arrows in connection with support member 14 as well as the rotary movement of the spindle 12, head portion 5 and bobbin 13 as well as of traveler 9 are well known in the art and may be of any conventional appropriate construction, such drive means together with the other frame parts have been omitted for sake of clarity of the present invention.

As pointed out hereinabove, the feed or entrainment member formed by the spindle head portion 5, may be of any suitable construction enabling sliding movement of the thread 2 along the periphery thereof.

5 Furthermore, the upper thread-guide member 6 may be of any suitable construction, for instance, may be constructed as open annular member 6a shown in FIGURES 6, 6A, as closed annular member 6b as shown by FIGURES 7, 7A, or as a sleeve disposed on the side of the spindle 12, and may be adjustable in the height and/or in the distance thereof with respect to the axis of spindle 12 or as shown in FIGURES 8, 8A as an annular member 6c supported on a rod 14 which may be disposed at an appropriate distance from the spindle 12. Additionally, other guide member or members, similar to guide member 6 may be provided therebelow in order to reduce even further the size of the balloon.

The thread-guide 3 may also be of any suitable construction, for example, of a plate having a V-shaped notch or an auger-like gimlet 3a with small diameter. The notched plate 3 may also be provided with a small retaining nose. These three different plate formations are shown respectively as 3b in FIGURES 3, 3A, as 3a in FIGURES 4, 4A and as 3c in FIGURES 5, 5A.

25 The upper guide member may also be mounted on a hinged member so as to enable temporary removal from its normal position.

The feed or entrainment member 5 may be formed integrally with spindle 12 or may be interchangeably secured thereto to enable variations in the diameter thereof, in the height thereof, in the profile thereof, in the material of which it is made, and in the degree of roughness of its surface. It may be knurled along the periphery thereof as shown by number 5a in FIGURES 9, 9A, provided with indentations or radial notches of slight depth as shown by members 5b and 5c in FIGURES 10, 10A, 11, 11A, and may be disk-shaped, cylindrical or in the form of a truncated cone as illustrated respectively in the figures just mentioned. It may also be made of metal, rubber, plastics or mineral material.

30 While I have shown and described one embodiment in accordance with the present invention, it is understood that the same is not limited thereto but is susceptible of many changes and modifications within the spirit of the present invention, and I intend to cover all such changes and modifications as encompassed by the appended claims.

I claim:

1. In a spinning machine provided with spindle means, traveler means rotatably disposed about said spindle means, and means for driving said traveler means, an arrangement for imparting a torsion to the thread to be spun prior to being wound on said spindle means comprising entrainment means for said thread attached to the upper end portion of said spindle means, guide means including a thread guide member arranged a distance above said entrainment means for maintaining the path of said thread in a fixed direction so as to intersect the axis of said spindle means, and an annular guide member rigidly connected to said thread guide member and substantially coaxial with and surrounding said spindle means, said annular guide member being located a distance below said entrainment means, the distance of said guide member and said annular guide member from said entrainment means and the construction of said members and said entrainment means being so dimensioned as to maintain said thread in continuous contact at all times with the periphery of said entrainment means and at a constant angle with the axis of said spindle means.

2. The combination according to claim 1, wherein said thread guide member is formed by a plate provided with a V-shaped notch.

3. The combination according to claim 1, wherein said entrainment means is knurled.

4. The combination according to claim 1, wherein said entrainment means is in the shape of a truncated cone.

5. The combination according to claim 1, wherein said entrainment means has a diameter at the most equal to that of said spindle means.

6. The combination according to claim 1, wherein said thread guide member is adjustable in height.

7. The combination according to claim 1, wherein said guide means further includes a movable lower guide member disposed below said annular guide member for reducing the size of the balloon.

8. The combination according to claim 1, further comprising means pivotably supporting said thread guide member to permit pivotal movement out of its normal position.
